CONVERSION OF HYDROCARBONS

Don R. Carmody, Hammond, Ind., assignor to
 Standard Oil Company, Chicago, Ill., a corpora-
 tion of Indiana

Application February 28, 1942, Serial No. 432,849

7 Claims. (Cl. 196—10)

This invention relates to a process for the production of gasoline of high octane number from normally gaseous hydrocarbons and pertains more particularly to an improved process for the alkylation of isoparaffinic hydrocarbons with selected normally gaseous olefinic hydrocarbons.

It is known that isoparaffinic hydrocarbons such as isobutane or isopentane can be alkylated by normally gaseous olefins such as isobutylene, normal butene, or propylene in the presence of sulfuric acid as a catalyst. It has also been discovered that under ordinary alkylating conditions alkylation by ethylene of isobutane or other similar hydrocarbons containing a tertiary carbon atom is not catalyzed by sulfuric acid. It has further been discovered that the olefinic gases other than ethylene can suitably be converted to the corresponding alkyl sulfates by absorption in sulfuric acid and these alkyl sulfates employed for alkylating isoparaffinic hydrocarbons in the presence of sulfuric acid under the usual alkylating conditions. In carrying out the step of absorbing olefins in sulfuric acid and thereby eliminating undesirable paraffinic hydrocarbons prior to the alkylation step, a loss is incurred in olefinic material due to the condensation or polymerization of the olefins to products of higher molecular weight which are not suitable for use in alkylation and which cannot be recovered for conversion to gasoline-like products.

It is an object of this invention to provide an improved process for the production of gasolines particularly suitable for aviation fuels by the treatment of paraffinic hydrocarbons containing a tertiary carbon atom with selected olefins. Another object is to provide an improved process for the production of a blended gasoline suitable in anti-knock characteristics, boiling range, and volatility for aviation fuel, by the alkylation of isoparaffinic hydrocarbons with substantially pure olefinic hydrocarbons under conditions suitable for optimum conversion of each type of olefinic hydrocarbon and blending the resulting alkylate. Another object is to provide an improved process for the production of aviation gasoline by carrying out an alkylation process in such a manner that the alkylate is formed under the most advantageous conditions for high yield and in such a manner that contamination with inert gases is substantially reduced. Further objects and advantages will become apparent as the description thereof proceeds.

The attached drawing which forms a part of

the specification is a simple flow diagram illustrating one preferred embodiment of my invention.

My process in brief includes the recovery of substantially pure ethylene from a refinery C_2 stream, the conversion of C_4 and/or C_3 olefins to the corresponding alkyl sulfates without substantial formation of polymerization or condensation products, the alkylation of an isoparaffinic hydrocarbon with the pure ethylene under alkylation conditions suitable therefor employing a Friedel-Crafts type catalyst, and alkylation of an isoparaffinic hydrocarbon with the alkyl sulfates under preferred alkylation conditions using sulfuric acid as a catalyst, and thereafter recovering the alkylates in the form of a balanced fuel suitable for aviation gasoline.

Referring now to the drawing, an ethylene-containing gas stream enters absorber 10 through line 11. The ethylene-containing gas stream is suitably obtained from the lighter gases recovered from the cracking, thermal or catalytic, of petroleum, or petroleum fractions, and may have been separated from gases of higher molecular weight by fractionation, absorption and stripping, etc. The ethylene gas stream will usually contain ethane as well as varying quantities of methane and hydrogen depending on the previous method of segregating the C_2 hydrocarbon. 20 Absorber 10 contains concentrated sulfuric acid, preferably of greater concentration than 90% H_2SO_4 and more desirably 94% H_2SO_4 or higher, which enters through line 12 at the upper portion of the absorber 10. The ethylene-containing gas stream enters the base of absorber 10 through line 11 and the addition of this ethylene-containing stream is regulated in such a way as to obtain concentrated sulfuric acid ester in the 25 bottom of the tower. Absorber 10 is maintained at pressures within the range from about atmospheric to about 100 atmospheres, preferably at about 30 atmospheres to about 50 atmospheres, and at a temperature within the range from about 0° F. to about 150° F., preferably about 75° F. to about 100° F. The unabsorbed gases, which will be mainly ethane together with any methane and hydrogen present, pass overhead from absorber 10 through line 13 and can be 30 discarded or used for fuel gas and other similar purposes.

The concentrated ethylsulfuric acid is passed into stripping tower 14 from absorber 10 via line 15 and enters at the upper portion thereof. A 35 gas stream containing unsaturated C_4 hydrocar-

bons or unsaturated C₃ hydrocarbons, or a mixture of the two, with or without the corresponding paraffins, enters stripper 14 through line 16. Although the unsaturated C₃ and/or C₄ hydrocarbons can be obtained from any suitable source, they are generally easily available, in petroleum refinery gas streams particularly from the depropanization or debutanization of cracked gasoline. Various methods are well known for fractionating and recovering normally gaseous hydrocarbons from gasoline and any of these may be employed. I especially prefer a fraction rich in C₄ olefins. Another source is from the dehydrogenation of natural gas butane or propane. The ethylsulfuric acid is added to stripper 14 and as the gas stream passes countercurrent therethrough the ethylene is liberated and propyl and/or butylsulfuric acid is formed. The ethylene of the ethylsulfuric acid is displaced by propylene and/or butylene and the ethylene freed without further absorption. At the same time, the polymerization of the C₃ and C₄ olefins to higher molecular weight hydrocarbons is substantially precluded. The stripper is so regulated as to temperature, pressure, and velocity of the gas stream passing therethrough that substantially only alkylsulfuric acid passes out the lower part of the stripper, while substantially the only olefin passing overhead is ethylene, although the saturated hydrocarbons which may have been present in the gas stream are thus withdrawn from the system. Stripper 14 is maintained at about 30° F. and at pressures within the range from about 1 to about 100 atmospheres, preferably at about 5 to about 25 atmospheres pressure.

The butyl sulfuric acid withdrawn from the base of stripper 14 is directed to sulfuric acid alkylator 17 via line 18. Sufficient additional strong sulfuric acid is added to alkylator 17 via line 19 and line 20 to maintain the concentration in the alkylator between about 90 and 100%, preferably about 95 or 96% H₂SO₄ based on the water content of the acid mixture. Isobutane from any suitable source (not shown) is added through line 21 and line 22 and can be mixed with the alkyl sulfates in line 18 prior to alkylator 17 or mixed with the sulfuric acid from line 19 via line 23 before injection into alkylator 17. Alkylator 17 is maintained at the usual alkylating conditions found optimum for a process of this type; for example, at a temperature within the range from about 20° F. to about 100° F., but preferably from about 40° F. to about 80 F., and under sufficient pressure to maintain the reactants in the liquid phase. The reactants are fed to the alkylator at a rate of about 0.01 to about 10 volumes of reactant per volume of strong sulfuric acid per hour. The feed should contain a mol ratio of isoparaffin to olefin absorbed in the acid within the range of from about 1:1 to about 10:1 and preferably about 4:1. Any suitable apparatus can be used which is capable of insuring intimate contact of the reactants and catalyst, together with means, if necessary, for controlling the temperature of the reaction. A portion of the emulsion of sulfuric acid alkylate, unreacted hydrocarbons, acid and alkylsulfuric acid is recycled through lines 24a, 30 and 20 to alkylator 17 and the remainder withdrawn through line 24 and directed to settler 25 in which stratification of the acid and hydrocarbon layers occurs. The hydrocarbons together with unreacted gases are withdrawn overhead via line 26, neutralized and washed (by means not shown), if desired, and directed to fractionator 27

via line 28. The acid from the base of settler 25 is withdrawn through line 29 and, if still of alkylating strength, can be recycled via line 30 to line 20 and alkylator 17. If the acid is substantially spent for alkylation but is not yet below 90% H₂SO₄ titratable acidity, it can be recycled to the ethylene absorption step via line 31 which joins line 12. If completely spent for either purpose, of course, it can be withdrawn via line 32.

10 It is to be noted that usually an acid having a titratable acidity of less than 90% H₂SO₄, or in that region, is comparatively ineffective for promoting the alkylation of isoparaffins with olefins or alkylsulfates. Apparently the titratable acid strength is determined in a large part by the amount of hydrocarbons in the sulfuric acid, and the acidity shown by ordinary titration is based on the weight of the sample which, of course, includes the hydrocarbons present. The acidity based on the water content of the sulfuric acid will still be of the order of 93 to 95% or higher, however, and is therefore eminently suitable for use in the absorption of ethylene. Accordingly, it is an important step in our process that the 15 partially or wholly spent acid from alkylation which still has a hydrocarbon-free acidity of 90% or greater be recycled to the ethylene absorption step.

20 The ethylene from stripper 14, together with any C₄ or C₃ paraffinic hydrocarbons originally 25 present in the gas stream from line 16 passes overhead through line 33 to alkylator 34 in which the ethylene is contacted with an isoparaffinic hydrocarbon in the presence of an aluminum halide-type catalyst. Although sulfuric acid does not catalyze the alkylation of an isoparaffin with ethylene, it has been found that very effective alkylation can be obtained if an aluminum halide-type catalyst such as aluminum chloride or aluminum bromide, or more advantageously an aluminum halide-hydrocarbon complex is employed for promoting the reaction. The aluminum halide can be used as such or supported on various materials such as clays, pumice, kieselguhr, alumina, etc. It can be introduced in the form of a slurry in an inert solvent or be present in the form of lumps over which the reactants pass. A particularly desirable type of catalyst is one formed by the reaction of aluminum chloride with a normally liquid hydrocarbon in the presence of a hydrogen halide activator and particularly with a paraffinic hydrocarbon, although aromatic or olefinic hydrocarbons are also useable. The reaction product is in the form of an aluminum halide-hydrocarbon complex, difficult to analyze, 30 liquid in form, and usually of modified activity, i. e., the extreme activity of pure aluminum chloride is reduced to a point where undesirable side reactions are minimized or eliminated.

35 Alkylator 34 is maintained at temperatures from about 0° to about 212° F. or higher and at superatmospheric pressures within the range from about 30 pounds per square inch to about 500 pounds per square inch, although I prefer that it be maintained within the range from about 40 to about 250 pounds per square inch. A preferred temperature includes the range from about 50° F. to about 150° F. and most desirably from about 110° F. to about 135° F. It is desirable to 45 add an activator such as a hydrogen halide, and more particularly hydrogen chloride, to the reaction, usually in amounts of 5% or less based on the aluminum chloride present, and it can be as low as 0.5%. Intimate contact between the reactants and the catalyst is necessary although it has been

found that the reaction can be carried out successfully if the reactants are passed upwardly through a deep pool of catalyst.

Activator is added through line 35 and catalyst through lines 36 and 37. An isoparaffin such as isobutane is added from line 21 and line 38 and can be injected directly into the ethylene stream in line 33 or sent directly to alkylator 34 via line 39. The hydrocarbon conversion products, together with unconverted hydrocarbons, are withdrawn from alkylator 34 through line 40 and sent to settler 41 wherein a separation is made between the hydrocarbons and any occluded or dissolved catalyst. A cooling coil or other similar temperature-reducing means can be inserted in line 40 to precipitate out dissolved aluminum chloride. The separated catalyst is withdrawn from settler 41 via line 42 and can be discarded through line 43 but preferably is recycled through line 44 to line 37 and alkylator 34 until substantially spent.

The hydrocarbons together with activator pass overhead from settler 41 through line 45 and through a washing and neutralizing system (not shown) to line 28 leading to fractionator 27. In fractionator 27, which can be any conventional apparatus for the separation of hydrocarbons of various boiling ranges, unreacted gases, which will be chiefly paraffinic hydrocarbons from gas stream 16, and excess unreacted isobutane from line 21 pass overhead through line 46 and can be discarded through line 47 or recycled through line 48 to line 21. In the event that the off-gases contain considerable amounts of normal butane or the normal butane tends to build up in the system, it may be desirable either to fractionate in such a manner as to eliminate the normal butane and recycle only the isobutane, or to direct the total off-gases through an isomerization unit I wherein the normal butane is converted to isobutane suitable for use in the alkylation systems. As a further modification it is quite within the scope of this invention to separate the normal butanes from the isobutanes and to direct only the normal butanes to isomerization system I and thence back to the alkylation system where they join the previously separated isobutanes.

Hydrocarbons heavier than aviation gasoline can be withdrawn from fractionator 27 through line 49. In the event that this fraction does not contain too great a quantity of hydrocarbons of very high molecular weight, it is quite possible to use these heavy hydrocarbons as an aviation "safety fuel," or it is equally within the scope of this invention to withdraw the hydrocarbons of safety fuel boiling range as a side stream (not shown) and discard only the heavy condensation product through line 49. A blended gasoline of high octane number, balanced volatility, and good lead response is withdrawn as a side stream through line 50. In the system described the chief product of alkylating isobutane, for example, with ethylene in alkylator 34 will be diisopropyl, while the alkylate from alkylator 17 will be chiefly isoctane, or isooctanes and isoctanes depending upon the exact olefins used in the process. The fraction withdrawn through line 50 therefore represents a product eminently suitable for use in aviation engines which demand not only high octane number but a fuel having a definite boiling range and certain volatility characteristics required for ease in starting not possessed by isoctane alone.

My process has the definite advantage that

ethylene is obtained in concentrated form and substantially free of diluents such as ethane, methane, hydrogen, etc. One of the gravest problems in the commercial production of diisopropyl from refinery light gas streams is concentrating the ethylene therefrom, and my process provides an extremely economical and advantageous process in that respect. Great difficulty has also been encountered in concentrating C₃ and particularly C₄ olefins by conversion to the alkyl sulfate in avoiding excess losses due to the conversion of a part of the olefinic feed to polymers and high boiling condensation products. By using ethylsulfuric acid as the absorption medium, the propylene and butylenes are not only converted substantially quantitatively to alkyl sulfuric acid, but there is little or no tendency for a part of the olefins to be polymerized or hydropolymerized without conversion. Furthermore, there is no dilution of the sulfuric acid alkylation catalyst due to the use of diluted, low concentration sulfuric acid for olefin absorption, which is the case under ordinary absorption conditions used for forming butyl sulfates. The acid strengths in my process are much more nearly identical. Ordinary absorption of mixed olefins in sulfuric acid either requires a different strength of acid for each particular olefin or varying pressures if the same strength acid is used throughout. When using ethylsulfuric acid this "selectivity" appears to be eliminated or reduced to such an extent that the loss of olefins is negligible.

Although I have designated the reaction product of ethylene and sulfuric acid as ethylsulfuric acid, and the reaction products of C₃ and/or C₄ olefins with ethylsulfuric acid as the corresponding alkylsulfuric acids, for the sake of simplicity, I wish to include any and all products formed during either of these reactions within the scope of my invention.

My process has been illustrated generally, and many details necessary or desirable for the operation of a commercial unit have been omitted for the sake of clarity and simplicity, but these details will readily be supplied by one skilled in the art. These details include such items as pumps, valves, heat exchangers, washing and purifying means, etc., all of which are well-known and their necessity understood. Although I have shown one preferred embodiment of my invention, it should be realized that this is by way of illustration and not by way of limitation, and that I intend to be bound only by the scope of the appended claims.

I claim:

1. A process for the production of a balanced fuel comprising the steps including contacting at least one olefinic hydrocarbon having more than 2 carbon atoms per molecule with ethylsulfuric acid whereby ethylene is liberated and an alkylsulfuric acid corresponding to said olefinic hydrocarbon is formed, contacting said liberated ethylene with an isoparaffinic hydrocarbon in the presence of an aluminum halide type catalyst under alkylation conditions, contacting said alkylsulfuric acid with an isoparaffinic hydrocarbon in the presence of strong sulfuric acid under alkylation conditions, recovering alkylate from each of said last mentioned contacting steps and blending said recovered alkylates.

2. A process for the production of a balanced fuel which comprises the steps of contacting ethylsulfuric acid with a stream of normally

gaseous hydrocarbons containing butylene and comprising predominantly olefins having more than two and less than five carbon atoms per molecule whereby ethylene is liberated and alkylsulfuric acid corresponding to said olefins is formed, contacting said liberated ethylene with isobutane under alkylation conditions in the presence of an aluminum halide catalyst to produce an alkylate predominating in diisopropyl, contacting said alkylsulfuric acid with isobutane in the presence of strong sulfuric acid under alkylation conditions to produce an alkylate comprising isoctane and recovering a balanced fuel comprising a blend of the diisopropyl and the isoctane produced in each of said last-mentioned contacting steps.

3. A process for the production of a balanced aviation fuel comprising the steps including forming ethylsulfuric acid from an ethylene-containing gas stream and sulfuric acid, contacting said ethylsulfuric acid with a normally gaseous hydrocarbon stream containing olefins having more than two carbon atoms per molecule under conditions whereby said ethylene is liberated from said ethylsulfuric acid and alkylsulfuric acid is formed corresponding to said olefins in said normally gaseous hydrocarbon stream, separating said liberated ethylene from said alkylsulfuric acid, contacting said liberated ethylene with an isoparaffinic hydrocarbon in the presence of an aluminum halide type catalyst under alkylation conditions, contacting said alkylsulfuric acid with an isoparaffinic hydrocarbon in the presence of strong sulfuric acid under alkylation conditions, recovering alkylate from each of said last mentioned contacting steps and blending said recovered alkylates.

4. A process for the production of a balanced aviation fuel comprising the steps including forming ethylsulfuric acid from an ethylene-containing gas stream and sulfuric acid, contacting said ethylsulfuric acid with a normally gaseous hydrocarbon stream containing olefins having more than two carbon atoms per molecule under conditions whereby said ethylene is liberated from said ethylsulfuric acid and alkylsulfuric acid is formed corresponding to said olefins in said normally gaseous hydrocarbon stream, separating said liberated ethylene from said alkylsulfuric acid, contacting said liberated ethylene

5 with an isoparaffinic hydrocarbon in the presence of an aluminum halide type catalyst under alkylation conditions, contacting said alkylsulfuric acid with an isoparaffinic hydrocarbon in the presence of strong sulfuric acid under alkylation conditions, recovering alkylate from each of said last mentioned contacting steps, returning sulfuric acid from said last mentioned sulfuric acid contacting step substantially spent for alkylation to said ethylsulfuric acid forming step, and blending said recovered alkylates.

10 5. A process according to claim 3 in which said isoparaffinic hydrocarbon is isobutane.

15 6. A process according to claim 3 in which said olefins in said normally gaseous hydrocarbon stream comprise predominantly olefins having four carbon atoms per molecule.

20 7. A process for the production of a balanced aviation fuel comprising the steps including contacting a light gas stream containing ethylene, ethane and lighter gases with sulfuric acid of greater than 90% H_2SO_4 content under conditions adapted to form ethylsulfuric acid, eliminating gases other than ethylene from said contacting step, contacting said ethylsulfuric acid with a C_4 stream containing olefins and paraffins countercurrently under conditions adapted to liberate ethylene and form butylsulfuric acid, recovering said liberated ethylene and contacting

25 30 said recovered ethylene with isobutane in the presence of an aluminum chloride-hydrocarbon complex under conditions adapted to promote the alkylation of said isobutane by said ethylene to hydrocarbons having predominantly six carbon atoms per molecule, contacting said butylsulfuric acid with isobutane in the presence of strong sulfuric acid under conditions adapted to

35 40 promote the alkylation of said isobutane by the butyl radical of said butylsulfuric acid, returning sulfuric acid from said last mentioned contacting step to said ethylene-stream contacting step when substantially spent for promoting said last mentioned alkylation, recovering alkylate from said aluminum chloride alkylation step and from said sulfuric acid alkylation step, directing said alkylates to a common fractionation system, and recovering from said fractionation system a balanced aviation fuel.

DON R. CARMODY.
